UNITED STATES PATENT OFFICE.

GEORGE E. TITCOMB, OF PHILADELPHIA, PENNSYLVANIA, ASSIGNOR TO THE DODGE COAL STORAGE COMPANY, OF NAUGATUCK, CONNECTICUT, A CORPORATION OF CONNECTICUT.

ROPE-CARRIER FOR MOVABLE BUCKET CONVEYERS.

SPECIFICATION forming part of Letters Patent No. 742,753, dated October 27, 1903.

Application filed August 22, 1903. Serial No. 170,448. (No model.)

To all whom it may concern:

Be it known that I, GEORGE E. TITCOMB, a citizen of the United States, residing in Philadelphia, Pennsylvania, have invented certain 5 Improvements in Rope-Carriers for Movable Bucket Conveyers, of which the following is a specification.

My invention relates to certain improvements in that class of hoisting mechanism in which a bucket-carrying trolley traverses a bridge structure and is operated by means of one or more ropes leading from the source of power to the bucket and trolley.

The object of my invention is to provide 15 means operated automatically by the trolley which will support the rope at one or more points between the trolley and the source of power, but will open automatically for the free passage of the trolley, as fully described 20 hereinafter.

In the accompanying drawings, Figure 1 is a transverse sectional view, on the line 1 1, Fig. 3, of sufficient of a bridge-hoist to illustrate my invention. Fig. 2 is a transverse sectional 25 view on the line 2 2, Fig. 3. Fig. 3 is a longitudinal sectional view showing a section of the bridge and one of the rope-supporting members. Fig. 4 is a perspective view showing the pivoted rails and connecting-frame. 30 Fig. 5 is a perspective view of one of the rope-supports, and Fig. 6 is a view of the intermediate yoke-frame.

A is the bridge structure, which may be of any length and design desired. This structure is supported at each end, and at one end 35 is the power mechanism for operating the trolley and the bucket. This is simply one form of supporting structure, and it will be understood that the structure may be modified as desired. Hung from the structure are the permanent rails B B, over which travels the trolley C. (Shown by dotted lines in Fig. 1.) These rails are held to fixed brackets b, secured at intervals to the main frame of the 40 bridge.

B' B' are pivoted rail-sections. These sections are pivoted at b' to the fixed bracket b, and the rails have a limited movement on their pivots.

45 B² is a yoke-frame, (clearly illustrated in

Fig. 4,) to which are pivoted the outer ends of the rails B' at b². The two rails of each section are held together by an intermediate yoke-frame B³. (Illustrated in Fig. 6.) The yoke-frame B³ is mounted in fixed guides A², 55 suitably braced and hung from the bridge structure A.

D D are two carriers for supporting the rope. These carriers move transversely in respect to the movement of the trolley and have flanged 60 wheels supported by transverse rails a', carried by the bridge structure. At the outer end of each carrier D is a flanged roller d', which when the carriers are forced together support the ropes leading to the trolley and 65 bucket.

Extending from the under side of each carrier D is a V-shaped guide d². The guides are so formed that if the rope should be under the carriers it will be directed by the guide d² 70 and will force its way through the space between the two carriers, as the tension on the rope is much greater than the spring-pressure to keep the carriers together.

The yoke-frame B³, to which the outer ends 75 of the rails B' are connected, is supported by a spring E, which rests on a plate e on the cross member A' of the bridge structure. A bolt e', attached to a head e², supported by the spring E, passes through the spring and 80 is attached to the cross member b³ of the yoke-frame.

Extending from each side of the yoke-frame B³ is an arm b⁴, to which is attached a link f, hung from an arm f' of a lever F. Each lever F is pivoted at f² to a bearing carried by the transverse member A' of the bridge structure. The long arm f³ of each lever F extends down to and engages a pin d³ on a carrier D, so that the downward movement of 90 the yoke-frame B³ will cause an outward movement of the carriers D, thus opening the passage to allow the bucket-carrying trolley and its ropes to pass through.

On the fixed guides A² are guards c and 95 stops c'. The stops limit the downward movement of the rails B'.

There may be any number of the devices above described on the bridge structure, according to the span of the bridge. It will be 100

seen that when the trolley moves away from the source of power at one side of the bridge it will travel first on the fixed rails B, then on the pivoted rails B', and the weight of the trolley will depress the rails and cause the rope-carriers to open to allow the trolley to pass, and as soon as the trolley leaves the pivoted rails B' the spring will cause the rope-carriers to close. Usually the rope is above the carriers; but in some instances when it is below it will force its way up through the space between the two carriers and then rest upon the supporting-rollers.

When the trolley is returned, the operation will be repeated. The rope-carriers being separated will allow the trolley to freely pass. Thus I am enabled to provide means for supporting the rope at intervals between the source of power and the trolley, which means is automatically operated by the trolley to release the ropes and to allow for the free passage of the trolley.

By the construction shown I am enabled to provide means for moving the rope-support away from the path of the trolley without shock to the rope-support, as the movable rails are of sufficient length to cause the trolley to gradually move the rope-support when coming in contact with it.

While I have shown a spring for supporting the yoke-frame, it will be understood that a weight may be used as an equivalent of the spring, and while I have shown two pivoted rail-sections, one abutting the other, a single pivoted section may be used, or a single pivoted rail connected to a single carrier may be designed; but I prefer to use the construction shown where possible.

I claim as my invention—

1. The combination of a movable carrier for a rope, a movable rail connected to said carrier, and a trolley to which the rope extends, the whole being so constructed that the weight of the trolley will move the rope-carrier and allow the trolley to pass, substantially as described.

2. The combination of a transversely-movable carrier for a rope, a fixed and a pivoted rail, said pivoted rail connected to said carrier, and a trolley to which the rope extends, the parts being so constructed that when the trolley passes from the fixed rail to the movable rail the carrier will be moved out of the path of the trolley and its rope, substantially as described.

3. The combination of the fixed rails, the pivoted rails, a yoke-frame supporting the outer ends of the pivoted rails, a spring carrying the yoke-frame, laterally-movable carriers for the rope, and mechanism connecting said carriers with the yoke-frame, and a trolley mounted on the rails, the parts being so arranged that when the trolley is on the pivoted rails its weight will cause the withdrawal of the laterally-movable carriers, substantially as described.

4. The combination of the fixed rails, the

pivoted rails, a frame secured to the outer ends of the pivoted rails, a spring for supporting said frame, laterally-movable rope-carriers, lever mechanism connected to the frame and to the rope-carriers, with a trolley arranged to travel on the fixed and pivoted rails, the parts being so arranged that when the trolley is on the pivoted rails its weight will cause the rope-carriers to open, substantially as described.

5. The combination in a bridge structure, of the fixed rails supported thereby, a series of pivoted rails forming continuations of the fixed rails, laterally-movable rope-carriers mounted in the fixed frame, a movable frame attached to the outer ends of the pivoted rails, means for supporting the movable frame, lever connections between said movable frame and the rope-carriers, a trolley mounted on said rails, the parts being so arranged that when the trolley is on the pivoted rails the rails will be depressed and the rope-carriers opened so as to allow for the passage of the trolley, substantially as described.

6. The combination of a fixed structure, fixed rails thereon, two rail-sections pivoted thereto, a yoke-frame connected to the outer ends of both sections, a spring supporting said yoke-frame to keep the rails normally in the raised position, laterally-movable rope-carriers mounted in bearings in the fixed frame, lever mechanism connecting the yoke-frame with the movable rope-carriers, so that when the trolley is on the pivoted rails its weight will overcome the pressure of the spring and cause the rope-carriers to part and allow for the free passage of the trolley, substantially as described.

7. The combination of a structure, fixed rails thereon, rails pivoted thereto and forming a continuation of the fixed rails, a frame to which the outer ends of the rails are attached, a spring for supporting the said frame, laterally-movable rope-carriers, guides therefor on the fixed frame, a lever on each side of the yoke-frame, a link connecting the short arm of each lever with the yoke-frame, the long arm of each lever being connected to a rope-carrier, the parts being so arranged that when the trolley is on the pivoted rail its weight will counteract the springs and will separate the rope-carriers, substantially as described.

8. The combination of the fixed rails, the pivoted rails forming a continuation of the fixed rails, a frame attached to the outer end of the pivoted rails, a spring for supporting said frame, laterally-movable rope-carriers, and means connecting the pivoted rails to said carriers, each of the carriers having a roller, substantially as described.

9. The combination of the fixed rails, the pivoted rails forming a continuation of the fixed rails, a frame attached to the outer end of the pivoted rails, a spring for supporting said frame, laterally-movable rope-carriers, means connecting the pivoted rails to the car-

riers, each of said carriers having a roller, and rope-guides on each carrier for directing the rope as it forces its way through the space between the carriers, substantially as described.

5. 10. The combination of the fixed frame, fixed rails secured thereto, rails pivoted to the fixed frame and forming a continuation of the fixed rails, a yoke-frame attached to the outer ends of the pivoted rails, a spring tending to hold the pivoted rails in the elevated position, rope-carriers, wheels thereon, fixed guides for the said wheels, a roller on

each rope-guide for supporting the rope, and lever connection between each rope-carrier 15 and the yoke-frame, so that when the trolley travels over the pivoted rails it will depress said rails and cause the rope-carriers to part, substantially as described.

In testimony whereof I have signed my 20 name to this specification in the presence of two subscribing witnesses.

GEORGE E. TITCOMB.
